(57) **CLAIM**

The ornamental design for a selector lever element, as
shown and described.

DESCRIPTION

FIG. 1 is a rear perspective view of a selector lever element,
showing our new design;

FIG. 2 is a front perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof;

FIG. 8 is a rear view thereof;

FIG. 9 is a rear perspective view of a selector lever element
according to a second embodiment;

FIG. 10 is a front perspective view thereof;

FIG. 11 is a left side view thereof;

FIG. 12 is a right side view thereof;

FIG. 13 is a top view thereof;

FIG. 14 is a bottom view thereof;

FIG. 15 is a front view thereof;

FIG. 16 is a rear view thereof.

FIG. 17 is a rear perspective view of a selector lever element
according to a third embodiment;

FIG. 18 is a front perspective view thereof;

FIG. 19 is a left side view thereof;

FIG. 20 is a right side view thereof;

FIG. 21 is a top view thereof;

FIG. 22 is a bottom view thereof;

FIG. 23 is a front view thereof; and,

FIG. 24 is a rear view thereof.

The broken lines shown throughout the various figures
depict additional structures that form no part of the claimed
design.
